INVENTOR:

G. MANGIALETTI

BY his ATTORNEY

Aaron L. Applebaum

UNITED STATES PATENT OFFICE.

GAETANO MANGIALETTI, OF BROOKLYN, NEW YORK.

COVER BACK AND HINGE.

Application filed October 15, 1926. Serial No. 141,851.

This invention relates to a combined cover back and hinge for wash tub covers or closures and has for its object to provide a novel and improved means for connecting said cover or closure whereby the hinges are concealed and presenting a neat appearance.

One of the objects of my invention is to provide in a cover back and hinge construction a novel and improved means for connecting a cover such as employed for wash tubs and the like wherein the hinge is totally concealed when said cover is closed presenting a smooth, even surface yet permitting said cover to be raised and swung up and over on the cover back when desired.

Another object of my invention is to provide a cover back preferably of enamel ware or of the same material as the cover, including a novel and improved cooperating hinge wherein the flanged, abutting edge of the cover may lie flush with the flanged edge of the cover back in one position and permitting the hinged cover to be raised and swung over and on the cover back in a second position.

A further object of my invention is to construct a cover back and hinge which will be extremely simple, easily assembled, neat in appearance, practical, durable, comparatively cheap to manufacture, capable of universal use in connection with standard types of stationary wash tubs and the like, and otherwise possessing mechanical advantages over the ordinary type of hinge now employed for the same purpose.

To enable others skilled in the art to more fully comprehend the underlying features of my invention that they may embody the same in the many practical advantages and uses to which it is capable, and illustrating a preferred form of the invention in the annexed drawings,

Fig. 1 is a perspective view showing the cover back and the cover when closed and the hinges concealed.

Fig. 2 is a partial view showing the cover open and the relation of the hinge to the cover back and cover.

Fig. 3 is a closed, end view of the cover back and cover.

Fig. 4 is an open, end view of the cover back and cover.

Fig. 5 is an enlarged, detail view showing the hinge.

Referring now to the drawings wherein

like reference characters designate corresponding parts throughout the several views, 5 designates the base and 6 the rear wall of a cover back, said rear wall being disposed at right angles to the base and formed integral therewith. The base is provided with end flanges 7 and angle plates 8 whereby the cover back may be positioned on the sides and rear wall of a tub, such as a stationary wash tub, shown in dotted lines by 60 Fig. 1.

The base of the cover back is also provided with a depending front flange 9 partially cut away at each end so as to permit the cover 10 and the connecting hinge to 70 swing upwardly in the manner shown by Fig. 2 of the drawing. This operation is effected by means of a double hinge construction comprising a plate 11 having an elongated slot 12 therethrough and attached 75 to the portion of the flange 9 adjacent the cut 13, by means of the threaded screws or bolts 14 and nuts 15.

The top edge of the plate 11 is rolled on itself forming a pivotal connection 16 for 80 the straight end 17 of a hinge pin or rod extending beyond the end of the plate, said rod being bent at right angles and curved upwardly as at 18 and then continuing in a straight end portion 19 in the same plane as 85 the opposite end portion. The complementary section of the hinge comprises a plate 20 provided with an elongated slot 21 therethrough for connection to the inside face or surface of the flange 22 of the cover, being 90 so connected thereto by the threaded elements 23 and nuts 24.

The plate 20 is formed with a tab 25 bent at right angles thereto, the inner edge of said tab being rolled on itself as at 26 forming a hinge connection for the straight portion 19 of the hinge pin or rod. The tab is adapted to swing with the curved portion of the rod through the cut out in the flange of the cover back and at the same time may 100 also pivot on the end portion of the rod. Furthermore, since the pivotal connections for the straight portions of the hinge pin or rod are located at the top and bottom of the hinge plates respectively, it will be 105 seen that the rear abutting flange of the cover and the depending flange of the cover back conceals the plates when the cover is closed. The top of the cover and the base 110 of the cover back are therefore in the same

horizontal plane forming a smooth surface from the front to the back of the wash tub or basin.

It will be clearly understood and appreciated that the double hinge employed permits the cover to not only rotate on the hinge pin or rod but permits it to swing outwardly and upwardly over and on the base of the cover back. In other words the cover permits of 10 a swinging movement relative to the base of the cover back but also a pivotal movement on the hinge pin or rod whereby it may be moved to its full open position.

While I have shown the ends of the plates 15 extending within the cut out portion of the depending flange it will be understood that the width of the cut out portion should only be sufficient to permit the free swinging movement of the curved portion of the bent 20 rod or hinge pin and the tab to which it is connected. However, the elongated slots in both the plates permit of sufficient adjustment to accommodate the screw or bolt holes in the depending flange and flange cover to 25 which the plates are fastened.

Having shown and described my invention what I now claim as new and desire to secure by Letters Patent of the U. S. is:—

1. In a device of the class described comprising a cover back having a base and rear wall, means for positioning the cover back on the top and at the rear of a stationary tub or the like, said base having a front depending flange, portions of said flange being cut away, and a cover having an abutting flange pivotally connected to the depending flange adjacent the cut out portions whereby it may be swung outwardly and upwardly on the base.

2. In a device of the class described comprising a cover back having a base and rear wall, means for positioning the cover back on the top and at the rear of a stationary tub or the like, said base having a front depending flange, portions of said flange being cut away, a flanged cover and concealed hinges connecting the cover to the said depending flange adjacent the cut out portions

whereby it may be swung outwardly and upwardly on the base.

3. In a device of the class described comprising a cover back having a base and rear wall, means for positioning the cover back on the top and at the rear of a stationary tub or the like, said base having a front depending flange having a cut out portion, a cover, and hinges connecting said cover to the depending flange, a portion of said hinges being movable through the cut out portion of the depending flange whereby the 55 said cover may be swung outwardly and upwardly on the base.

4. In a device of the class described comprising a cover back having a base and rear wall, means for positioning the cover back on the top and at the rear of a stationary tub or the like, said base having a depending front flange, portions of said flange being cut away, a flanged cover and double hinges connecting the cover back and cover at said cut out portions whereby the latter may be 65 swung outwardly and upwardly on the base of the cover back in its open position, and the flanges of the cover back and cover brought into abutting relation when the cover is in 70 its closed position.

5. In a device of the class described comprising a cover back having a base and rear wall, means for positioning the cover back on the top and at the rear of a stationary tub or the like, said base having a depending front flange, a flanged cover and double hinges connecting the flanges of said cover back and cover, said depending flange of the cover back being partially cut away whereby the cover may be swung outwardly and 80 upwardly on the base thereof to its open position, the base of the cover back and the top of said cover lying in the same plane and the flanges of said cover back and cover 85 abutting each other concealing the said hinges when said cover is in its closed position.

In testimony whereof I affix my signature.

GAETANO MANGIALETTI.
